UNITED STATES PATENT OFFICE

ERNEST WANAMAKER, OF CHICAGO, ILLINOIS, ASSIGNOR TO KULP THEFTPROOF LAMP COMPANY, OF CHICAGO, ILLINOIS, A CORPORATION OF ILLINOIS

LOCKING MEANS FOR ELECTRICAL APPARATUS

Application filed December 10, 1924. Serial No. 754,897.

This invention relates to locking means or devices for locking electrical apparatus within supporting sockets and has particular reference to devices of this character for rendering electric lamp bulbs, plug fuses, and the like, theftproof.

The subject matter of this invention comprises an improvement over the device disclosed in the patent to D. R. Coughlin, Re-
10 issue Number 15,836, dated May 13, 1924, which discloses a theftproof electric lamp so made that it may be inserted in a socket of the usual construction and yet which cannot be stolen or removed from the socket until after 15 the lamp bulb or electrical apparatus has become broken and displaced.

The objects of this invention include the provision of a very simple, durable and inexpensive construction for the purposes desired, 20 such construction embodying substantially the minimum number of parts and being dependable and certain in its operation.

In the accompanying drawing, which illustrates one embodiment of my invention, Figure 1 is an elevational view illustrating an assembled lamp embodying my invention; Figure 2 is a central sectional view through the base of a lamp embodying this invention and showing the parts in assembled relationship, and Figure 3 is a detailed sectional view of a portion of the lamp base member and shell contact.

In general, the invention as illustrated may comprise an electric lamp bulb, 10, of standard construction, a base member, 11, adapted to be securely cemented upon the stem or neck, 12, of the lamp bulb and a threaded shell contact, 13, for embracing the base member, 11.

It will be understood that I do not desire to 40 restrict the application of my invention to its use with lamp bulbs, since various other types of electrical apparatus, such as plug fuses, thermo-ionic valves, and the like, may be substituted for the lamp bulb, 10, and rendered theftproof in accordance with this invention.

The base member, 11, may comprise a cylindrical shell contact, 14, upon which the threaded shell contact, 13, is loosely fitted. The shell contact, 14, may be provided with 50 one or more pin or rivet members as at 15,

which may engage or extend through the shell contact, 13, for the purpose of initially fixing the shell contact against rotation relative to the lamp base and lamp.

It will be observed that when the base member, 11, is rotated as by grasping the bulb 10 for inserting the lamp into a receptacle, the shell contact, 13, will also be rotated because of the rivet connection, 15. In this manner, the threaded shell contact may be screwed 60 into the receptacle. The lamp or other electrical apparatus may be thus inserted and removed from the receptacle as often as desired, as long as no abnormal rotational forces are exerted thereon. However, when it is 65 desired to render the device theftproof, the threaded shell contact may be screwed home in a receptacle and then if an abnormal and additional force is exerted to screw the device further inwardly the rivet or rivets as 70 at 15 will be sheared, as indicated in Figure 3. Thereafter, the shell contact 13 will be free for rotational movement in respect to the base member 11 and, accordingly, when an attempt is made to remove the lamp from its 75 receptacle by turning the bulb the base member, 11, will merely freely rotate within the threaded shell contact and without exerting rotational force upon such contact. Hence, the bulb or other apparatus, together with 80 the base member, 11, will be merely rotated and cannot be removed.

After the lamp or other electrical apparatus has become worn out so that it is desirable to remove the same, the operator may 85 place a canvas or other bag over the glass portion of the lamp and thereupon break the lamp. The canvas bag will retain the particles of broken glass. Access may then be had to a flanged edge, 16, on the threaded 90 shell contact for removal thereof by the use of pliers or other suitable tools.

The threaded shell contact, 13, may be permanently retained against longitudinal movement in respect to the lamp by means of 95 the flange, 16, at the lower edge of the contact and a flange, 17, at the upper edge or end thereof. The flange, 16, is adapted to be spun over and to abut a beaded portion, 18, formed upon the base member near its 100

lower edge. The flange, 17, is adapted to be spun over a flange portion, 19, at the upper edge of the base member, 11.

From an inspection of Figure 2, it will be observed that the lower portions of the flange, 16, may be located at a point which will be well within the receptacle member in which the lamp may be inserted. In this way, the receptacle member serves to prevent access to the threaded shell contact member and accordingly this member cannot be turned either inwardly or out of the receptacle by tampering while the lamp or other electrical apparatus is in operative condition.

As shown in Figure 2, the interior of the base member, 11, may be filled with a suitable cement to cement the base member to the neck of the bulb in the conventional manner. At the upper end of the base member, 11, a center contact, 20, may be positioned and held in place by the use of an insulating end piece, 21, which may be tightly fitted or molded into the upper end of the base member, 11. Lead wires, 22 and 23, from the lamp filament or other electrical devices may be electrically connected to the contacts, 13 and 20, respectively, in any suitable and well known manner.

It will be noted that the rivet or pin member, 15, as illustrated, is of a small cross-section so that it may be readily sheared by the relative rotation of the base member and the contact, 13. The exact dimensions of the pin, of course, will depend upon the strength of the material of which it is made. A section of soft iron wire has been found to provide suitable material. As indicated in the drawings, the rivet passes through perforations in the contacts, 13 and 14, the rivet being of such diameter as to closely fit these perforations. The inner and outer ends of the rivet member are preferably slightly headed, as indicated, in order to prevent them from drawing through the perforations before the shearing action takes place. After the shearing action has been effected, the outer end of the rivet may drop out, as indicated in Figure 3, whereas the inner end of the rivet will remain within the beaded portion, 18. The shearing action is such that the rivet will be sheared along a predetermined line and with a smooth cut. The sheared ends of the rivet hence will thereafter offer no resistance to the free turning of the threaded shell contact.

While I have described my improvements in detail and in connection with a preferred form thereof, I do not desire to be limited to such details or form, since many changes and modifications may be made and the invention embodied in various different forms without departing from the spirit and scope of the invention in its broader aspects. Therefore, I desire to cover all modifications

and forms coming within the language or scope of any one or more of the appended claims.

Having thus described my invention, what I claim as new and desire to secure by Letters Patent of the United States is:

1. An electric lamp comprising a bulb, and a shell-contact and an insulated center contact therefor, means fixing the shell contact against longitudinal movement in respect to said bulb member, a rivet initially fixing said bulb against rotation in respect to said shell contact and purposely designed to be sheared by the exertion of a predetermined force to effect such rotation, a filament in said bulb, and means for maintaining electrical connection between said filament and said shell and center contacts regardless of the rotation of the bulb member with respect to the shell contact.

2. In an electric lamp, a bulb, a center contact and a shell contact therefor, metallic means for initially securing the bulb against rotation in respect to said shell contact, said means being purposely designed to be sheared for permitting the bulb to be independently rotatable after the exertion of a predetermined force to effect independent rotation thereof, and means for maintaining electrical connection between the lamp filament and the shell and center contacts regardless of the rotation of the bulb.

3. In a theft-proof electric lamp, a bulb, a center contact and a shell contact therefor, the shell contact being screw threaded for engagement with the conventional socket and also provided with metallic means for securing the bulb against rotation in respect to said shell contact while the lamp is being inserted into a socket, said metallic means being purposely designed to be sheared along a predetermined line for releasing the bulb in respect to the shell contact after the exertion of abnormal force to effect independent rotation thereof.

4. In combination, an enclosure for electrical apparatus, a cylindrical shell mounted on said enclosure, means for preventing unauthorized removal of the enclosure from the shell, said shell being provided with means for engaging a supporting receptacle by turning movement of said shell, and riveting means initially fixing said enclosure against rotation in respect to said shell to normally permit insertion and removal of the shell in respect to a receptacle by turning said enclosure, said riveting means being purposely designed to be disengaged by the exertion of a predetermined force to effect further inward turning of the enclosure in respect to the receptacle.

5. In combination an electric lamp bulb member provided with a substantially cylindrical supporting shell, said shell being provided with means for engaging a support-

- ing receptacle by turning movement of said shell, rivet means for securing said shell to the bulb member and against rotation in either direction whereby the lamp may be used in the ordinary way if desired, but said rivet means being purposely designed to become disengaged for permitting said bulb to be rotatable in respect to said shell after being subjected to an abnormal rotational force tending to turn the lamp into a socket, whereby the lamp is made theft-proof and cannot be thereafter turned out of the socket until the bulb is broken to expose portions of said shell.
6. In combination, an electric lamp bulb provided with a shell contact, means including a pin for mounting thereon the shell contact to be initially fixed against rotation in either direction in respect thereto, said means being purposely designed for permitting said bulb to be freely rotatable in respect to said contact in either direction after being subjected to a predetermined disrupting force, and means for supplying electrical energy to the lamp through said shell contact after such rotation of the bulb.
7. In combination an electric lamp bulb provided with a substantially cylindrical supporting shell, said shell being provided with means for engaging a supporting receptacle by turning movement of said shell, means including a pin for mounting said shell on the bulb to be initially fixed against rotation in either direction in respect thereto, said pin being purposely designed for permitting said bulb to be rotatable in respect to said shell in either direction after being subjected to a predetermined force to disengage said pin, and means for preventing removal of the bulb from the shell.
8. An incandescent lamp consisting of a bulb, and center and shell contacts therefor, the shell contact being screw-threaded in the conventional manner and also provided with inwardly protruding metallic means to secure the shell contact in respect to the bulb so as to permit of the lamp being screwed into a socket by simple rotation of the bulb, said metallic means being purposely designed to be deranged and released by the application of an abnormal force to effect rotation of the bulb after the lamp is screwed home so that the bulb will then rotate independently of the shell contact, and means for maintaining electrical connection between the lamp filament and the contacts notwithstanding such independent rotation of the bulb.
9. A theft-proof electric lamp comprising a bulb, a substantially cylindrical metallic shell permanently cemented to the stem thereof and electrically connected to one of the lamp filament terminals, a center contact connected to the other filament terminal, a threaded shell contact embracing said metallic shell, the peripheral edges of said threaded contact being turned inwardly and said metallic shell being formed with a beaded portion cooperating with one of said inwardly turned edges to prevent relative longitudinal movement of said shell and contact, and rivet means at said beaded portion for preventing said threaded contact from turning in respect to the bulb while the lamp is being inserted in a receptacle by turning the bulb, said rivet means being purposely designed to be disengaged by the exertion of a predetermined force to effect further inward turning of the bulb in respect to a receptacle.
10. In combination an electric lamp bulb, a substantially cylindrical supporting and contact carrying member permanently cemented thereto, a threaded shell contact embracing said member and rivet means adjacent the peripheral edge nearest the body of the bulb on said contact for initially fixing said bulb against rotation in respect to said contact to normally permit insertion and removal of the threaded shell in respect to a receptacle by turning said bulb, but said rivet means being purposely designed to be disengaged by the exertion of an abnormal force to effect further inward turning of the shell in respect to a receptacle.
11. A theft-proof base for electric lamps, comprising an inner shell, an outer screw-threaded shell surrounding the inner shell, means to prevent relative longitudinal movement of the two shells, and a frangible pin extending through the two shells and serving to cause the conjoint movement of the two shells in the act of screwing the base into a usual lamp socket and breaking upon further turning of the base in the same direction and thereby preventing the rotation of the screw-threaded shell.
12. A theft-proof base for electric lamps, comprising an inner shell in which a lamp bulb is adapted to be fixed, an outer screw-threaded shell surrounding the inner shell, means to prevent relative longitudinal movement of the two shells, the two shells having aligned perforations, and a frangible pin applied transversely to the two shells through their perforations and fixed therein and connecting the two shells against relative rotary movement and adapting them to turn together to an extent sufficient to permit the seating of the lamp in the socket and thereafter upon further turning of the lamp in the same direction being broken thereby preventing the rotation of the screw-threaded shell and consequently the removal of the lamp intact.
13. A theft-proof base for electric lamps, comprising an inner shell having a circumferential bead provided with a transverse perforation and an outer shell having a transverse perforation, said shells arranged one within the other, means on the outer shell engaging the inner shell to prevent relative

longitudinal movement of the two shells, and a frangible connection for the shells applied in the perforated bead and in the perforation of the outer shell and adapted to permit the insertion of the lamp in a socket and by further movement in the same direction to sever the connection and thereby prevent removal of the lamp intact.

14. A theftproof base for electric lamps, comprising an inner shell, a shell surrounding the inner shell, means to prevent relative longitudinal movement of the two shells, including a frangible pin extending through the two shells and serving to cause the conjoint movement of the two shells in the act of screwing the base into a usual lamp socket and breaking upon further turning of the base in the same direction, and thereby preventing the rotation of the second-mentioned shell.

15. A theftproof base for electric lamps, comprising an inner annular member secured to the lamp, a shell surrounding the inner member screw-threaded for engagement with the usual electric lamp socket, means to prevent relative longitudinal displacement of the shell and inner member, a transversely positioned frangible pin cooperatively associated with the inner member and the outer screw-threaded shell and serving to cause the conjoint movement of the two shells in the act of screwing the base into the usual lamp socket, and breaking upon further turning of the base in the same direction and thereby preventing the rotation of the screw-threaded shell.

In witness whereof, I have hereunto subscribed my name.

ERNEST WANAMAKER.
